UNITED STATES PATENT OFFICE.

HERBERT E. BARTSCH, OF CHICAGO, ILLINOIS, ASSIGNOR TO UNIVERSAL DRAFT GEAR ATTACHMENT CO., A CORPORATION OF ILLINOIS.

BRAKE MECHANISM.

Application filed March 8, 1926. Serial No. 93,032.

This invention relates to brake mechanism and more particularly to brake mechanism for railway cars.

One of the objects of the invention is the provision of new and improved means for supporting the multiplying or reversible lever and attendant mechanism.

Another object of the invention is the provision of new and improved means for supporting the multiplying lever whereby the vibration incident to the movement of the car will cause the support to automatically move to inoperative position when the brakes are released.

15 A still further object of the invention is the provision of brake operating mechanism that is cheap to manufacture, easily assembled, efficient in operation, rugged in construction, and that is not likely to be come deranged or get out of order.

Other and further objects and advantages of the invention will appear from the following description taken in connection with the accompanying drawings, in which

25 Fig. 1 is a longitudinal vertical section of a portion of a car showing the invention in position thereon;

Fig. 2 is a plan view of a portion of a car, showing the invention in position thereon;

30 Fig. 3 is a top plan view of a portion of a car showing a portion of the invention in position thereon;

Fig. 4 is a side elevation with parts in section and parts broken away;

35 Fig. 5 is a detail sectional view on the line 5—5 of Fig. 4; and

Fig. 6 is a vertical section on broken line 6—6 of Fig. 4.

On the drawings, the reference character

40 10 designates a railway car having the longitudinally arranged sills 11 and the transverse members 12, 13 and 14. The step for supporting the brake drum 15 is shown at 16 and the brake staff at 17. The brake

45 staff is provided with the usual wheel or lever 18 for rotating the brake staff for applying the brakes, as is usual in such constructions. For convenience of description only, the end of the car toward the right 50 in Fig. 1 will be considered the front of the car.

The car is provided with the usual air brake cylinder 19, the piston 21 of which is connected to the brake lever 22 for applying

the brakes with compressed air in the usual manner.

Suitable means are provided for applying the brakes by hand power from the brake staff 17. This means comprises an expandable and contractible connection 20 between the brake staff and lever, including a reversible or multiplying lever 23 which is so constructed and arranged that on the initial rotation of the brake staff the slack in said connection will be taken up quickly, and on further movement the brakes will be applied with great force.

As shown, one end of the connection 20 is in the form of a flexible member or cable, as the chain 21, which is secured to the 70 drum 15 and is adapted to be wound thereon. The opposite end of the connection 20 is also in the form of a flexible member or cable, as the chain 27 which extends about the grooved reversible lever 23 and is secured in the anchor member 24 in any suitable manner. As shown, it is attached in the manner disclosed in patent to Wrigley, No. 1,543,467. The anchor member is connected to a support 25 which is rigidly connected to the frame work of the car.

75 The cable or chain 27 is connected to the reversible lever 23 as at 30 in any suitable manner. The reversible lever and the means for connecting the cable thereto may 80 be and preferably are substantially the same as that disclosed in patent to Camp and Bartsch, No. 1,543,470, June 23, 1925, and need not be further described.

85 The two chains or cables 21 and 27 are preferably connected by a rod 28 which is slidably supported by guides 29 and 31. The use of a rod eliminates the necessity of taking up a great amount of slack in applying the brakes, as would be necessary were 90 a single cable employed between the brake drum and the anchor, owing to the sag in the cable.

95 The reversible lever 23 is rotatably mounted in a bracket or jaw 32 which is slidably mounted on the inclined support 33. The bracket 32 is of any suitable form, that shown being bifurcated to form a jaw and having one or more convex bearing surfaces 34 for slidably engaging the support 33. 100 The furcations are united at their lower rear portions, as at 40.

105 The bracket or jaw 32 is connected to the

brake beam in any suitable manner. As shown, a flexible connection, as the cable or chain 38, is employed for this purpose. The connecting portion 40 is provided with a horizontal slot 36 and a vertical slot 37 intercepting each other and adapted to receive adjacent links of one end of the chain 38 for securing the same thereto. The vertical slot 37 forms shoulders 42 against which the link 43 of the chain engages to anchor the same. A cotter pin 44 in back of the vertical link 45 is adapted to prevent the disengagement of the chain from the jaw member. The slots are so constructed that the chain 38 cannot be removed unless the link 45 is first turned to vertical position, after which the chain may be disengaged by moving the same forwardly. The opposite end of the chain 38 is secured to the lever 22 and piston 21 as clearly shown in Fig. 1 of the drawings. The use of a flexible connection between the brake lever and the jaw 32 permits the brakes to be applied by the piston 21 without affecting the hand brake mechanism.

The support 33 is attached at one end to the cross member 12 and has its opposite end offset and attached to the sill 11 as clearly shown in Fig. 3.

In applying the brakes by hand the brake staff 17 is rotated to wind the chain 21 on the drum 15 which in turn will rotate the reversible lever 23. The initial rotation of the lever 23 will take up the slack rapidly and further rotation will set the brakes with the application of considerable power. The jaw 32 will slide upwardly along the guide or support 33. When the brakes are released the vibration of the car will cause the jaw 32 to slide downwardly along the support 33 by gravity.

It is thought from the foregoing taken in connection with the accompanying drawings that the construction and operation of my device will be apparent to those skilled in the art and that various changes in size, shape, proportion and details of construction may be made without departing from the spirit and scope of the appended claims.

I claim as my invention:

1. In a brake mechanism for railway cars, a brake lever, a brake staff, an expansible and contractible connection between said staff and lever, said connection comprising a reversible lever, an inclined support, and means slidably mounted on said support for supporting said reversible lever.

2. In a brake mechanism for railway cars, a brake lever, a brake staff, a connection in-

cluding a reversible lever operatively connected to said staff and lever, a connector jaw in which said lever is pivoted, inclined supporting means, and means for slidably mounting said connector jaw on said supporting means.

3. In a railway brake mechanism, an inclined support, a jaw having a slot for engaging said support, a reversible grooved lever journaled in said jaw to rotate in said slot, and cable anchoring means at one end of said jaw.

4. In a brake mechanism for railway cars, a brake staff, a brake lever, an expansible and contractible connection including a supporting member, between said staff and lever, and means for supporting said member and for causing the same to move to elevated position during the application of the brake, said member being returned by gravity to inoperative position when said brakes are released.

5. In a brake mechanism for railway cars, an inclined support, a jaw member having a slot for receiving said support, and a reversible lever rotatably mounted in said slot, said jaw member being provided at its lower portion, opposite said reversible lever, with means for anchoring a chain.

6. In a brake mechanism, a jaw member for supporting a reversible lever, an inclined supporting bar, said member being provided with a slot for receiving said supporting bar, one end of the lower portion of said member being provided with aligned openings extending transversely therethrough and the opposite end being provided with vertical and horizontal intersecting slots for forming an anchor for a chain.

7. In a railway brake mechanism, a brake staff, a brake lever, expansible and contractible mechanism between said staff and lever, an inclined supporting member, means slidably mounted on said member for supporting a portion of said mechanism, said means sliding in the direction of said staff during the application of the brakes and sliding by gravity in the opposite direction when the brakes are released.

8. In combination with the underframing of a railway car, brake operating mechanism located beneath said underframing, said mechanism comprising a quick takeup device, inclined supports secured to said underframing, and means for slidably mounting said device on said supports.

In testimony whereof I affix my signature.

HERBERT E. BARTSCH.
